ARTICLE SHAKING MECHANISM

Eibe A. Wilckens, Baltimore, Md., assignor to
Crown Cork & Seal Company, Inc., Baltimore,
Md., a corporation of New York

Original application June 8, 1938, Serial No.
212,573. Divided and this application May 8,
1942, Serial No. 442,279

2 Claims. (Cl. 259—75)

The present invention relates to an article shaking mechanism, the application being a division of my application for Article handling apparatus, filed June 8, 1938, Serial No. 212,573, which matured into Patent 2,304,982, dated December 15, 1942.

In the packing of a number of types of small, light articles in shipping receptacles, it is desirable that the articles be firmly settled in the receptacles so that the latter need be no larger than necessary. In addition, adequate settling of the articles insures that they will not be free to move about during shipment and thereby become scratched. This latter is extremely important in the handling of articles such as container caps or closures which have a lithographed decoration thereon and may have a serrated edge which will scar adjacent caps.

An important object of the invention is the provision of an apparatus which will settle articles in packing receptacles.

Another object of the invention is the provision of a shaking apparatus of such design that packing receptacles of different sizes will be securely supported thereon for shaking movement.

The shipping receptacles in which articles such as closures are packed vary in size and shape, usually in accordance with their capacity. It is, therefore, desirable to provide a shaking apparatus which will hold various types of receptacles against movement relative to the shaking apparatus.

A further object is the provision of a shaking means actuating structure of optimum simplicity.

In accordance with the above object, the shaking platform is so connected to a controlling member or valve that its movements will determine the position of the controlling member. As a result, the platform serves as a timing device for the actuating structure.

Other objects and advantages of the invention will be apparent from the following specification and drawings.

In the drawings:

Figure 1 shows the shaking apparatus of the present invention in plan, the view showing the apparatus in association with the cap counting apparatus of said original application;

Figure 2 shows an electrical circuit for controlling the shaking apparatus;

Figure 3 is a side elevation of the shaking mechanism, showing one platform in vertical section;

Figure 4 is a central vertical sectional view of the actuating cylinder included in the shaking mechanism;

Figure 5 is a detail view of the device illustrated in Figure 4, the view being on the line 5—5 of Figure 4; and

Figure 6 is a vertical sectional view through a selector valve used with the shaking mechanism.

Figure 1 shows the shaking mechanism of the present invention as used with the cap counting apparatus of said original application. When the shaking mechanism is thus used, two shaking platforms 46 and 46' are provided so that caps or other articles may be delivered to a packing receptacle supported on one of the platforms, for example, platform 46, while an already filled receptacle is being removed from the other platform 46' and an empty receptacle placed thereon. Such an arrangement must include means to cause the caps to be delivered to a spout above the platform 46 which supports the receptacle to be filled, as well as means to shake only the platform 46.

Figure 2 diagrammatically shows the electrical circuit included in the apparatus of said original application to obtain the above controls.

Referring to Figures 1 and 2, the numeral 28 designates a hopper device which positions caps on edge for movement through a counting mechanism 38. The counting mechanism 38 includes cams 120 and 140 rotated by movement of the caps through the counting mechanism as described in said original application. The circuit of Figure 2 includes a lead 152 extending from a source of current to one side of a solenoid 151. The cam 120 actuates contacts 125 and 126 which, when moved to engaged position, will complete a circuit through lead 152, solenoid 151, lead 150 and thence to the source of current through a lead 150'. Energization of solenoid 151 will, through a cam mechanism disclosed in said original application, control the position of a guide plate positioned in outlet line 43 of the counting mechanism 38 so that the counted caps will move either through the spout 44 above shaking platform 46 or through the spout 45 above the other shaking platform 46'.

A lead 215 extends from lead 152 to one side of each of two solenoid valves 214 and 215 respectively associated with platforms 46 and 46'. A pawl and ratchet mechanism, also operated by solenoid 151, will rotate a contact device 40 to place the proper solenoid valve 214 or 215 in the return side of this circuit. For example, when the contactor 148 is in the position illustrated in Figure 2, only the valve 215 will be in position for operation, since current will flow to this valve through leads 152 and 215' and then

through lead 218 to fixed contact 208b and through a metal core in the container 40 to fixed contact 208. Fixed contact 208 is connected by a lead 210 to a switch including blades 131 and 141, the former being connected to the return lead 150' to the source of current. The cam 140 controls the contacts 131 and 141 and when these contacts are brought together, as will occur periodically during the rotation of cam 140, according to the number of caps passing through the counting mechanism, valve 215 will be actuated to cause the shaking mechanism 46' associated therewith to be actuated. As described in said original application, the position of contactor 40 will not change until the desired number of caps have been placed in the receptacle on platform 46' under control of counter 38.

The contactor 40 has the metal core described above covered by an insulating sleeve 148 including a continuous cut-out in the path of contact 208 so that this will always be in engagement with the metal sleeve. Shorter cut-outs 205 and 206 are arranged opposite the contacts 208a and 208b and these cut-outs are so arranged with respect to each other that the contacts 208a and 208b will alternately bear on the metal core.

By the above construction of contactor 40, as well as by the remainder of the circuit disclosed, when the solenoid 151 has placed the guide device in position to deliver caps through the chute 45, the valve 215 which controls the platform 46' beneath that chute will be the only platform which will be shaken by the action of the contacts 131 and 141. On the other hand, when solenoid 151 has moved the guide device to direct caps through the spout 44, contactor 40 will be actuated to place the valve 214 associated with platform 46 in the circuit with blades 131 and 141.

The solenoid valves 214 and 215 are of identical construction, each solenoid generally comprising, as illustrated in Figure 6, a coil 220 and an armature 221, the armature being provided at its lower end with a needle valve 223 adapted to seat in the upper end of a valve passage 224 opening to an outlet port 225. The upper end of passage 224 opens to a chamber 226 having an inlet port 227 in communication therewith. When coil 220 is deenergized, the needle valve 223 will seat in the port 224 by its own weight, thereby cutting off communication between the inlet port 227, which communicates through a line 228 with a source of compressed air, and the outlet port 225, which, in the case of solenoid 214, communicates with the shaking cylinder 48 by a line 228a. The outlet port 225 of solenoid 215 communicates with the shaking cylinder 48a through a line 228b.

The shaking cylinders 48 and 48a are of identical construction, each cylinder including a piston chamber 230 which is pivotally supported as indicated at 231 in supports 232. A piston 47 is mounted for reciprocation in the chamber 230, the piston 47 being fixed to a piston rod 234 which has its lower portion extending down through a packed bore in the lower wall of the piston chamber to be pivotally connected as indicated at 235 to one end of the corresponding shaking platform. The upper portion of the piston rod 234 extends through a packed bore in the upper end wall of piston chamber 230, the guided mounting of piston rod 234 in both the upper and lower end walls of the piston chamber insuring that the piston rod will move rectilinearly with respect to the chamber.

The reciprocation of piston 47 within the piston chamber 230 to effect oscillation of the corresponding platform is effected by actuation of a slide valve 237 moving in a valve chamber 238 which extends longitudinally of the cylinder 48 and communicates with the upper end of the piston chamber through a port 239 and with the lower end of the piston chamber through a port 240. The air inlet line 228a communicates with valve chamber 238 intermediate the ends of the latter.

Valve 237 has a groove 241 extending longitudinally of the same, which groove is always in communication with the inlet pipe 228. Adjacent its upper end, valve 237 is reduced to form a transverse groove 242 and a similar groove 243 is provided adjacent its lower end. The upper end of valve 237 is cut away as indicated at 244, this cut-away portion 244 being constantly open to the atmosphere and being intermittently positioned opposite the upper piston chamber port 239. Just below the lower valve groove 243 another groove 245 is provided in the valve 237, this groove being long enough to extend out of the valve chamber 238 and thereby adapted to intermittently place the piston chamber port 240 in communication with the atmosphere.

Valve 237 includes at its lower end an extension or rod 237a which projects entirely out of the valve chamber and carries a friction device 246 which moves between plates 247 depending from the cylinder structure.

The friction device 246 comprises two friction shoes 248 held in a bracket 249 fixed to the sides of valve rod 237a by welding as shown at 249a in Figure 5. A spring 250 extends through apertures 251 in the brackets and valve rod to force the friction shoes apart and to maintain them in close contact with the plates 247. This arrangement insures that the valve will remain in the vertical position to which it is moved by the receptacle or container supporting platform 46, as hereafter described, and against both the action of gravity and the pressure of the fluid moving through the valve.

The lower end of bracket 249 includes lateral flanges 252 and the extreme lower end of valve rod 237a is provided with laterally extending flanges 253 positioned in the path of movement of arms 254 on the near end of the corresponding shaking platform 46.

The operation of either cylinder 48 or 48a is as follows:

When the valve or controlling element 237 is in the lowered position shown in Figure 4, compressed air will enter through line 228a and flow downwardly through grooves 241 and 243 to enter the piston chamber port 240, thereby forcing the piston or driving member 47 upwardly to swing the near end of the corresponding shaking platform upwardly. During such movement of the piston, the upper piston chamber port 239 is in communication with the atmosphere through valve port 244, the upper transverse groove 242 of valve 237 being below and out of communication with upper piston port 239. When the near end of the platform 46 swings upwardly, the upper surface of the arms 254 will strike against the lower surfaces of the flanges 252 on bracket 249, thereby moving the valve rod and valve upwardly so that the upper transverse groove 242 of the valve will be opposite the upper piston chamber port 239 while the groove 245 of valve 237 will move opposite the lower piston chamber port 240 to place the latter in communication with the

atmosphere. As a result, compressed air will enter the upper portion of the piston chamber to drive the piston downwardly and when the arms 254 of platform 46 strike the flanges 253 at the lower end of the valve rod, the valve will be returned to the position of Figure 4.

The pivotal mounting of the cylinders 48 and 48a on their bearings 232 will permit the pistons to swing somewhat with the movement of the platform. The air inlet connections 228a and 228b are either flexible hose or include a joint adjacent the cylinders 48 and 48a to permit swinging of the cylinders.

The platforms 46 and 46' are of identical construction, each platform being pivotally supported by pins 260a extending into bearings 260 and the platforms being positioned alongside each other as shown in Figure 1 so that one platform will be beneath the spout 44 and the other beneath the spout 45. The pivot pins 260a are fixed to their platforms in such position that each platform is slightly off-balance, thereby insuring that at the conclusion of any shaking movement of a platform, the latter will always move to an inclined position and hence its valve 237 will be in either extreme upward or downward position. This arrangement will, of course, prevent a valve 237 from stopping in such position as to close both of the ports 239 and 240.

In order that packing receptacles of various sizes will be securely centered and retained on the platforms during their oscillation or shaking, each platform includes a base plate 261 having bars 262 welded to its upper surface adjacent the side edges thereof and, at its inner end, a cross bar 263 of the same height as the bars 262. As indicated in Figures 3 and 4, plates 262a and 263a overlie the bars 262 and 263 to build up a substantially high edge or wall about the edges of the plate 261. Within each corner of the framing edge thus formed is positioned a right angled bracket 264, brackets 264 being of less height than the framing edge.

As shown in the right-hand portion of Figure 1, the above arrangement enables various sizes of boxes to be securely held on the oscillatory platforms. For example, a box of relatively small capacity and of substantially square outline such as indicated at R' may be positioned between the side elements 262 of the framing edge, with its front and rear corners in contact with the faces 264a of the right angled members 264. Also, a box of substantially similar capacity but of oblong outline may be positioned entirely within the right angled members 264, as indicated by the dot and dash lines R². A box of somewhat larger outline indicated at R³ can be seated upon

the right angled members with its side walls in contact with the inner surfaces of the side bars 262 and its inner end in contact with the end bar 263. In order to further hold a box of this size in position, blocks 266 each having a plate 266a welded thereto to make them of the same height as the plates 262a are provided at the forward ends of the side bars. A still larger receptacle, indicated at R⁴ can be seated on the upper surfaces of the framing walls. In order to hold such a box more secure, right angled elements 268 are provided on the upper surface of the framing wall at the rear corners thereof and strips 269 are provided along the side edges of the framing walls at the front ends thereof.

Rubber blocks 270 may be secured to the floor beneath the ends of the shaking platforms to absorb vibration.

It will be further understood that the invention is not limited to the details of construction shown in the drawings and that the phraseology employed in the specification is for the purpose of description and not of limitation.

I claim:

1. A receptacle supporting and shaking platform for shaking apparatus comprising a plate element, means projecting upwardly from said plate element to bound areas in which receptacles may be seated and held against sidewise movement, said means including a plurality of angled members each comprising two legs extending at right angles to each other, said members being positioned at the corners of a rectangular area with their legs extending along two adjacent sides of such area so that receptacles may be seated within the area defined by the adjacent sides of said legs and also within the areas defined by the opposing ends of said legs.

2. A receptacle supporting and shaking platform for shaking apparatus comprising a plate element, means projecting upwardly from said plate element to bound areas in which receptacles may be seated and held against sidewise movement, said means including a plurality of angled members each comprising two legs extending at right angles to each other, said members being positioned at the corners of a rectangular area with their legs extending along two adjacent sides of such area so that receptacles may be seated within the area defined by the adjacent sides of said legs and also within the areas defined by the opposing ends of said legs, and means between said angled members and the edges of the plate element and projecting above said angled members to support a larger receptacle above said angled members.

EIBE A. WILCKENS.
